UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

OILING DEVICE FOR ROCK DRILLS.

Application filed November 29, 1921. Serial No. 518,549.

To all whom it may concern:

Be it known that I, LEWIS C. BAYLES, a citizen of the United States, and a resident of Easton, county of Northampton, and 5 State of Pennsylvania, have invented a certain Oiling Device for Rock Drills, of which the following is a specification, accompanied by drawings.

This invention relates to fluid actuated 10 rock drills, more especially of the hammer type, but relates particularly to an oiling device for lubricating the front end parts of a machine in which automatic rotation is provided for the drill steel.

15 The objects of the invention are to improve upon and simplify such type of oiling device and produce a self-contained oiling system wholly within the front head of the machine.

20 Further objects of the invention will hereinafter appear and the invention is shown in one of its preferred forms in the accompanying drawings, in which—

Figure 1 is a side elevation of a rock drill 25 partly in vertical section on the broken line 1—1 of Figure 3,

Figure 2 is a horizontal sectional view of the machine on the line 2—2 of Figure 1, looking in the direction of the arrows, and

30 Figure 3 is a horizontal sectional view of Figure 1 on either one of the lines 3—3 looking in the direction of the arrows.

Referring to the drawings, a "jackhamer" has been selected to illustrate the invention, 35 only so much of the operative parts of the machine being shown in detail as will enable the invention to be understood. The cylinder A has the usual back end parts and handle B secured together by the bolts C. Motive fluid is supplied at the inlet D in the distributing valve chest E. The fluted forward extension F of the reciprocating hammer piston is indicated in sliding but non-rotating engagement with the 40 chuck G revoluble in the front head H, which is secured to the cylinder by means of the side bolts J. The shank of a drill steel K extends into the chuck G in position to receive the blows of impact of the hammer 45 extending F.

I have found that oil chambers L may be conveniently and readily formed in the walls of the front head and supplied with oil through an opening O adapted to be closed by 50 the oil plug P. In order to provide inner

walls for the chambers L, and yet permit communication with the internal parts of the machine, I insert a perforated sleeve Q in the front head preferably from the rearward end. The perforations R in the sleeve 60 Q opposite the chambers L permit the lubrication of the rotating chuck G of the machine. The sleeve Q also forms a bearing and guide for the chuck G and in the present instance the sleeve Q abuts against 65 the internal shoulder S in the front head, and is thus held in longitudinal position.

I claim:

1. In a rock drill, the combination with a cylinder and reciprocating piston, of a front head having oil chambers in its walls, a separate means forming an inner wall for said chambers, means for introducing oil into said chambers and ports affording communication between the said chambers and 75 the interior of the front head.

2. In a rock drill, the combination with a cylinder and reciprocating piston, a front head and rotating chuck therein, of means for oiling the rotating chuck, comprising 80 oil chambers formed in a portion of the front head, a perforated sleeve forming the internal walls of said chambers and permitting communication between the oil chambers and the interior of the sleeve, and 85 means for supplying lubricating material to said chambers.

3. In a rock drill, the combination with the cylinder and reciprocating piston, of a front head having chambers in its walls, 90 a sleeve within the front head covering said chambers and having perforations affording communication between the chambers and the interior of the sleeve, a chuck rotatable within said sleeve, and means for supplying lubricating material to said chambers 95 for lubricating the chuck.

4. In a rock drill, the combination with a cylinder and a reciprocating piston, a front head and rotating chuck therein, an 100 oil chamber formed in said front head, a perforated sleeve forming the internal wall of said chamber and providing a bearing for said chuck, and means for supplying a lubricant to said chamber for lubricating the 105 chuck.

In testimony whereof I have signed this specification.

LEWIS C. BAYLES.
